No. 882,835.

PATENTED MAR. 24, 1908.

J. E. MCGILLIVRAY.

DEVICE FOR ATTACHING CROSS ARMS TO TELEGRAPH POLES.

APPLICATION FILED JAN. 21, 1907.

FIG. I.

UNITED STATES PATENT OFFICE.

JOHN E. MCGILLIVRAY, OF WALLA WALLA, WASHINGTON.

DEVICE FOR ATTACHING CROSS-ARMS TO TELEGRAPH-POLES.

No. 882,835.

Specification of Letters Patent. Patented March 24, 1908.

Application filed January 21, 1907. Serial No. 353,273.

To all whom it may concern:

Be it known that I, JOHN E. MCGILLIVRAY, of Walla Walla, county of Wallawalla, State of Washington, have invented certain new 5 and useful Improvements in Devices for Attaching Cross-Arms to Telegraph-Poles or the Like, of which the following is a specification.

The object of my invention is to produce not only an improved device for securely at- 10 taching cross-arms to telegraph poles or the like, but one which also performs the additional and novel function of assisting in adjusting the relationship of the cross-arm to the pole before rigidly securing it in position 15 for service.

What constitutes my invention will be hereinafter specified in detail and succinctly set forth in the appended claims.

In the accompanying drawings, which con- 20 stitute a part of this application, Figure I is a plan of a plate of metal, from which, preferably, my device is to be cut and struck out. The upper part of the plate is shown as cut away to form the top lugs of the fixture, the 25 line for the crease and cut to form the shelf and bottom lug being indicated by dotted lines. Fig. II is a perspective view showing my fixture complete, the bottom lug being struck out and the shelf bent up at right 30 angles thereto. Fig. III is a perspective view illustrating my fixture applied to a section of a cross-arm and looking at it from below, the main bolt being shown in place, and the parts of the fixture obscured by the 35 cross-arm being shown in dotted lines. Fig. IV is a view similar to Fig. III but looking at the cross-arm and fixture from above, and illustrating also a section of the pole to which the cross-arm and fixture is, by intervention 40 of the main bolt, secured. Fig. V is a vertical section of a portion of the subject matter of Fig. IV, taken through the center of the fixture and showing the main bolt and top and bottom lag-screws in elevation, one of the 45 lateral lag-screws and one of the lateral bolts being shown in dotted lines so far as obscured by the body of the cross-arm.

Referring to the numerals on the drawings, 1 (compare particularly Figs. I and II) 50 is the body part of my fixture, which is made, preferably, of a plate of No. 12 gage steel, although the weight of the metal employed may be varied, at will. From opposite sides of the body part proceed lugs, by which the 55 plate may be secured to the pole. It is pref-

erably provided with an upper medial-lug 2 and two upper lateral-lugs 3 and 4. The upper lugs 2, 3, and 4, are formed from the body of the plate by recesses 5 and 6 cut out of the metal. A medially disposed lower 60 lug 8 is cut, as by a die, from the body of the plate on three sides 9, 10, and 11, while from the body of the plate, along the line 12, the portion of the plate severed along the lines 9, 10, and 11, is struck up at right angles to the 65 body portion 1 of the plate to form a shelf 15. Each of the lugs is provided with a screw hole, indicated, respectively, by numerals 16, 17, 18, and 19, while the shelf 15 is provided with two screw-holes 20 and 21. The body 70 part 1 of the fixture is penetrated by a single medially located screw-hole 22 for the accom- modation of a main bolt 23, which in prac- tice unites the cross-arm 24, pole or support- 75 ing-member 25, and the intermediate fixture, as clearly shown in Fig. IV of the drawings. The apertures 16, 17, 18, and 19 are, in serv- ice, filled with lag-screws 26, 27, 28, and 29. 30 and 31 indicate lateral-bolts, which, intro- 80 duced through the apertures 20 and 21, re- spectively, serve to rigidly unite the cross- arm and fixture.

In practice, the fixture is first attached to the cross-arm 24 by means of the bolts 30 and 31, introduced through their respective 85 apertures 20 and 21, the bolts being firmly secured in place by their respective nuts. In this position, the body part 1 and the lugs 2, 3, 4, and 8, respectively, are located in the same plane, which is at right angles to the 90 plane of the shelf 15, as shown in Fig. II. The cross-arm, with the fixture attached in the manner last specified, is ready to be se- cured to the pole 25, which is accomplished, initially, by means of the main bolt 23 that 95 passes through the pole 25, cross-arm 24, and intermediate fixture, as shown in Fig. IV, apertures to correspond to the aperture 22 being provided in the several members re- ferred to for the accommodation of the bolt 23. 100

The securing together of the cross-arm 24, intermediate fixture, and pole 25, is securely effected by the introduction, through the apertures provided for it in the several mem- bers, of the bolt 23, but without other pro- 105 vision the cross-arm may turn upon the bolt 23 as an axis, the fixture, having its body part and lugs in the same plane, offering no resistance to said movement, but merely constituting, in effect, a flat washer between 110

the cross-arm 24 and its pole 25. Next, in order to secure the cross-arm fixedly to the pole, as required in service, the arm is first leveled and is then fastened by the insertion 5 of the lag-screws 26 and 29, through the lugs 2 and 8, respectively, into the pole 25, the apertures 16 and 19, which receive said lag-screws being substantially in vertical alinement with the aperture 22, which accommodates the main bolt 23. After the relative 10 positions of the cross-arm and pole have been obtained by the insertion of the lag-screws 26 and 29, as specified, the lugs 3 and 4 are then bent or driven back against the face of the 15 pole 25 and lag-screws 27 and 28 are inserted, through the apertures 17 and 18 therein, into the body of the pole. When all the parts, in the manner specified, are secured, the cross-arm is securely braced to the pole in proper 20 relative position and with the required resistance to displacement sufficient to counter-act all usual strain in service.

The foregoing specification is deemed to be sufficient to enable one skilled in the art to 25 understand and to construct the same. It may, however, be not amiss to add that the width of the fixture is approximately the average width of the pole top, and fixtures may run in sizes to accommodate poles of 30 different dimensions. The width of the shelf 15 preferably corresponds to the width of the cross-arm, which it is designed to support, and the height above the shelf is preferably substantially equal to the length of 35 the shelf, or in other words, the width of the fixture.

It has been specified that the fixture is preferably made of sheet metal in the manner specified. Such method of construction 40 is preferred for the sake of economy, but it is obvious that the essential features of the device would be present in any construction in which the body part 1, with its lugs 2, 3, 4, and 8 are initially disposed at right angles to 45 each other, the lugs 3 and 4 being of a flexibility which permit of their being bent back into position to enable them to perform their respective functions after the fixture has been trued to position for employment in 50 service.

What I claim is:

1. A device of the kind described, comprising a plate provided with a body part, upper and lower lugs in the same plane, and 55 a shelf located substantially at right angles thereto, whereby it may be assembled and adjusted with other devices, substantially in the manner specified.

2. A device of the kind described, comprising a body part, upper and lower medial 60 lugs, lateral lugs lying in the same plane, and a shelf located substantially at right angles thereto, the body part, lugs, and shelf being provided with apertures, whereby the device 65 may be secured to a cross-arm and to a pole,

respectively, the lateral lugs being adapted to be bent back and secured to the pole.

3. A device of the kind described, comprising a body part and lugs in the same plane and a shelf substantially at right angles 70 thereto, the said body part, lugs, and shelf being provided with apertures for the several reception of members for securing the device to a cross-arm and to a pole, in service, substantially as set forth. 75

4. A device of the kind described, comprising a body part, shelf and lug made of sheet metal, the lug and shelf being cut one from the other, and the shelf struck up at right angles to the lug and body part. 80

5. A device of the kind described, comprising a body part, shelf, and lug made of sheet metal, the body part and lug being in the same plane, and the shelf being at right angles to the body part and lug. 85

6. The combination with a telegraph pole and a cross-arm, of an intermediate fixture adapted to rest against the surface of said pole, means for securing said fixture to the cross-arm and to the pole, and additional 90 means for directly securing the fixture to the pole.

7. The combination with a telegraph pole and a cross-arm, of an intermediate fixture adapted to rest against the surface of said 95 pole, means for securing said fixture to the cross-arm and to the pole, said fixture being provided with laterally disposed lugs, and means separate from said lugs for securing the same to the pole. 100

8. A device of the kind described, comprising a body part adapted to be secured to a cross-arm, and to present when so secured a flat surface against a telegraph pole, and means for securing said body part to the pole. 105

9. A device of the kind described, comprising a body part provided with a medial aperture for the reception of a member for initially securing the device to a pole, and additional means for securing the device 110 fixedly to a pole.

10. A device of the kind described, comprising a body part adapted to be secured to a cross-arm, of means for initially securing the device to a pole adapted for the purpose 115 of first leveling the cross-arm, and means for securing the device after its initial adjustment fixedly to a pole.

11. The combination with a telegraph pole and a cross-arm, of a single intermediate fixture, means medially located with reference to said fixture for initially securing the cross-arm and fixture to the pole, and additional means for securing said parts fixedly together. 120

12. The combination with a telegraph pole and a cross-arm, of an intermediate fixture secured to the cross-arm and presenting against the pole a surface nonresistant to movement of the cross-arm, and a plurality 125 130

of means for uniting said members, one means for initially leveling the cross-arm and the other for fixedly securing the parts together.

5 13. The combination with a telegraph pole and a cross-arm, of a fixture for uniting them together, means for initially uniting, for purposes of adjustment, the pole, cross-arm, and fixture, and means for fixedly securing those members together after adjustment.

14. The combination with a cross-arm and fixture united thereto, of a telegraph pole, means for initially uniting the arm and attached fixture to the pole for the purpose of adjustment, and means for fixedly securing said members together after adjustment.

15 15. A device of the kind described, comprising a body part adapted to be secured to a cross-arm, medially disposed means for securing it to a telegraph pole, and laterally disposed additional means for securing it to the pole, both means for securing the device

to the pole being respectively complete and self-sufficient.

16. In a device of the kind described, the combination with a fixture adapted to be secured to a cross-arm, and means serving to hold the cross-arm and fixture yieldably to a pole so as to provide for subsequent adjustment or leveling of the fixture preparatory to the final fastening of fixture to pole.

17. The combination with a cross-arm and fixture, of a telegraph pole, means serving to hold the cross-arm and fixture yieldably to the pole so as to provide for subsequent adjustment or leveling of the fixture preparatory to the final fastening of fixture to pole.

In testimony whereof I have hereunto signed my name in the presence of two subscribing witnesses.

JOHN E. MCGILLIVRAY.
